UNITED STATES PATENT OFFICE.

LYMAN J. COOK, OF SILVER CREEK, NEW YORK, ASSIGNOR OF ONE-HALF TO J. IN B. WEBSTER, OF SILVER CREEK, NEW YORK.

WINDOW-SASH.

No. 873,211.

Specification of Letters Patent.

Patented Dec. 10, 1907.

Application filed May 4, 1907. Serial No. 371,810.

To all whom it may concern:

Be it known that I, LYMAN J. COOK, of Silver Creek, in the county of Chautauqua and State of New York, have invented certain new and useful Improvements in Window-Sash; and I do hereby declare the following to be a full, clear, and exact description of the invention, such as will enable others skilled in the art to which it appertains to 10 make and use the same.

My invention relates to an improvement in window sash and it consists in the details of construction as will be more fully described and pointed out in the claims.

15 In the accompanying drawings, Figure 1 is a view of a sash embodying my invention portions of the inner and outer frames being broken away. Fig. 2 shows the inner and outer frames detached, and Fig. 3 is a view 20 in section through the sash and glass.

1 represents the main frame which in my improvement constitutes the outer frame of the sash. This outer frame 1 is recessed or rabbeted on its inner edge thus forming a 25 continuous shoulder 2 which forms a support for the edges of the glass plate. This shoulder is straight and is faced with asbestos or other suitable cushioning material 3 against which the glass plate bears, and which compensates 30 for, or takes up any imperfection in the glass and makes the joint absolutely impervious to water.

That portion of frame 1 in rear of the shoulder 2 is beveled as shown at 4, so as to 35 permit the glass to be freely placed in position against the cushion 3, and is of a size sufficient to receive the inner frame 5, which latter bears against the inner face of the glass and holds the latter solidly against the 40 cushion 3 which as before stated, faces or lines shoulder 2. The frame 5 necessarily conforms to the shape of the opening in the main frame and its outer edge is beveled as at 6, the bevel on the outer face of the inner 45 frame 5 being greater or more acute than that on the main frame 1, so as to allow space for compressive movement of the inner frame. The outer edge of the perimeter of the inner frame 5 is constructed to fit or bear 50 against the inclined seat 4 of the outer frame 1, as shown in Fig. 3, thus leaving a gradually increasing space between the beveled faces of the two frames, from the inner faces of the former inwardly to the glass, which permits 55 the inner frame to be forced solidly against

the glass and to yield to compensate for any inequalities in the glass. This inner frame 5 is beveled on its outer exposed face so as to present a finished appearance, and is secured in place by screws or nails, preferably the 60 former. The outer face of the shoulder 2 is also beveled and in a finished and painted sash will present the appearance of a sash when the glass is held in place by putty.

With my improved sash, the glass is 65 placed in position and is removable from inside of the room and can be removed quickly and readily by simply withdrawing the screws which secure the inner rectangular frame 5 in place. Again by beveling the 70 seat for the inner frame, and also beveling the perimeter of the inner frame, the glass can be forced against the cushion and held there solidly, thus preventing any rattling of the glass in the sash and also forming a 75 joint that will effectually resist the entrance of water as well as exclude dust and dirt.

My improvement while primarily designed for houses, may also be used on car windows and picture frames.

80 A sash so constructed is exceedingly simple, and inexpensive; the glass may be removed and replaced from the inside without removing the sash from the frame; dispenses altogether with the putty joint, and is neat 85 in appearance and thoroughly practical.

It is evident that changes in the construction and relative arrangement of the several parts might be made without avoiding my invention and hence I would have it understood that I do not restrict myself to the particular construction and arrangement of parts shown and described, but,—

Having fully described my invention what I claim as new and desire to secure by 95 Letters-Patent, is,—

1. A window sash, comprising an outer frame having a continuous shoulder against which the edges of the glass rests, and an inclined seat in rear of said shoulder, and an 100 inner frame fitting within the outer frame and provided with a perimeter inclined at a different angle from that of the inclined seat on the outer frame and resting on the latter, the front edge of said inner frame adapted 105 to bear against the glass and hold the latter against the shoulder.

2. The combination with an outer frame having a continuous shoulder, and a yielding cushion covering the inner face of said shoul- 110

der, the portion of the frame from the shoulder to the inner face of the sash being inclined outwardly, of an inner rectangular frame having a perimeter which is inclined at a 5 different angle from that of said inclined portion of the outer frame and means for securing said inner frame to the outer frame in rear of the shoulder.

3. The combination with an outer frame 10 having a shoulder and an inclined face in rear of said shoulder, of an inner frame located within the outer frame and having an inclined outer face disposed at a different

angle from that of the inclined face of the outer frame, and means for securing the 15 inner frame to the outer frame and clamping a glass between said inner frame and the shoulder on the outer frame.

In testimony whereof, I have signed this specification in the presence of two sub- 20 scribing witnesses.

LYMAN J. COOK.
